UNITED STATES PATENT OFFICE.

JAMES PORTEOUS, OF FRESNO, CALIFORNIA.

PLOW.

SPECIFICATION forming part of Letters Patent No. 380,052, dated March 27, 1888.

Application filed December 24, 1887. Serial No. 258,932. (No model.)

To all whom it may concern:

Be it known that I, JAMES PORTEOUS, of the city and county of Fresno, State of California, have invented an Improvement in 5 Plows; and I hereby declare the following to be a full, clear, and exact description of the same.

My invention relates to that class of plows in which a single beam is made to carry two 10 plow-bottoms; and my invention consists in the combination, with a single straight beam, of two plow-bottoms and in the form of standards carrying said bottoms, said standards being secured directly to the beam and bent 15 outwardly in opposite directions, whereby the requisite width between the lines of travel of the plow-bottoms is obtained.

My invention further consists in the novel 20 form of the standards and in the flanges by which they are bolted to the beam. In plows of this class, where a single beam carries two plow-bottoms, it is usual to bend the beam, so as to provide for the separation of the plow-bottoms, and in some cases, where a straight 25 beam is used, blocks of wood have been bolted to the sides of the beam, so as to secure the necessary separation.

It is the object of my invention to secure the required width in the most simple manner, and by the most effective construction 30 avoiding both the bent beam and the blocks with the straight beam, and using instead a single straight beam and bolting the standards directly to it, the separation of the plow-bottoms being effected by bending outwardly the 35 standards.

A further object is to secure the standards in such a way as to best resist the twisting strain which results from their being bent.

40 Referring to the accompanying drawings, Figure 1 is a perspective view. Fig. 2 is a plan. Fig. 3 is a view showing a single vertical flange on top of the standard. Fig. 4 is a view showing a double flange.

45 A is a single straight plow-beam.

B is one plow-bottom in front.

C is the second plow-bottom following, and D are the handles.

E are the standards by which the plow-bottoms 50 are secured to the beam. These are bent outwardly in opposite directions, and are bolted above directly to the beam. The outward and opposite bend of the standards provides for the necessary separation of the lines 55 of travel of the plow-bottoms, and I need not,

therefore, resort to bending the beam or interposing blocks (which are liable to twist) between the standards and the beam. In order, however, to afford sufficient space for the earth to turn over between the standards, I 60 must make the bend in said standards wholly at the top, so as to throw their bodies as far apart as is required. It will be seen, therefore, that it is not possible to bend them anywhere but at the top. Now, on account of 65 the bend in the standards, the pressure against the plow-bottoms occasions a twisting strain on the standards, and in order to resist this to the best advantage I have the following construction: The top of each standard is bent 70 over horizontally, forming the flange e, which is bolted up under the beam; but this is not sufficient, as I must have a bearing on one or both sides of the beam. The backwardly bent vertical flange e', bolted to the side of the 75 beam, answers for one side when such is sufficient, or when I need a bearing on the other side I have a second vertical flange, e", passing upon the other side of the beam and bolted thereto; but this second flange is forward of the first one, so that their bolts will 80 not interfere or unduly weaken the beam.

I am aware that bent standards are not, broadly, new, and I do not claim such; but in this class of plows such standards, when 85 forming part of the general structure, render it possible to provide a plow of the simplest character and yet wholly effective in construction.

Having thus described my invention, what I 90 claim as new, and desire to secure by Letters Patent, is—

1. In a plow, the straight beam, in combination with the plow-bottoms and the oppositely-bent standards having a horizontal 95 flange bolted up under the beam and vertical flanges bolted on each side thereof, substantially as herein described.

2. In a plow, the straight beam, in combination with the plow-bottoms and the oppositely-bent standards having a horizontal flange bolted up under the beam and vertical flanges one in advance of the other and bolted on each side of the beam, substantially as herein described. 100

In witness whereof I have hereunto set my hand. 105
